UNITED STATES PATENT OFFICE.

JULES HUMBRECHT, OF FRIEDENAU, NEAR BERLIN, AND IGNATZ PECHAN, OF STEGLITZ, NEAR BERLIN, GERMANY, ASSIGNORS TO THE FIRM OF OPTISCHE ANSTALT C. P. GOERZ AKTIENGESELLSCHAFT, OF FRIEDENAU, NEAR BERLIN, GERMANY.

PERISCOPE WITH ENTRANCE AND DEFLECTION PRISM.

Application filed August 23, 1921. Serial No. 494,499.

(GRANTED UNDER THE PROVISIONS OF THE ACT OF MARCH 3, 1921, 41 STAT. L., 1313.)

To all whom it may concern:

Be it known that we, JULES HUMBRECHT, a citizen of the German Republic, and resident of Friedenau, near Berlin, Germany, 5 and IGNATZ PECHAN, a citizen of the Austrian Republic, and resident of Steglitz, near Berlin, Germany, have invented certain new and useful Improvements in and Relating to Periscopes with Entrances and 10 Deflection Prisms, of which the following is a specification (for which patent applications have been filed in Germany, February 25, 1916; Austria, filed December 13, 1917; Hungary, filed December 31, 1917).

15 This invention relates to a periscope, particularly for submarines, of that kind which permits observation not only in substantially horizontal direction but also in a direction towards objects waving in the air, 20 such as aircrafts. Periscopes of this kind are provided with an entrance reflector rotatable about an axis transversely to the main tube of the instrument.

The invention consists in the construction 25 of a periscope of this kind with changeable magnification having a specially small diameter at the light entrance end. For securing this result the periscope is provided in accordance with the invention with a 30 deviating prism inserted in the path of the rays behind the light entrance reflector, said prism being so shaped and positioned that it receives the rays coming from the entrance reflector and emits same after 35 double reflection in the direction of the main tube of the instrument.

40 Further objects of the invention and constructional means for securing same will appear from the following specification with reference to the annexed drawings.

45 Fig. 1 shows an axial section through the upper end of a periscope in accordance with the invention and illustrates the optical elements of the instrument with omission of the main part of the mechanical means for adjustment.

50 Fig. 2 shows a longitudinal section through the upper end of the instrument casing with the mechanical means for adjustment with omission of the main part of the optical elements, and indicating some of them in elevation.

Fig. 3 is a sectional view of an adjusting device for one of the optical elements.

Figs. 4 and 5 show the construction of the 55 operating handle near the ocular of the instrument in elevation and partly in section.

The upper end of the periscope is designated with the numeral 1. The instrument casing is made water-tight at its upper end 60 by a plain glass plate 2 which is arranged inclined to the tube 1. The light entrance reflector is formed by a right angled triangular prism 3. The deviation prism which in accordance with the invention is 65 arranged behind the light entrance reflector is designated 4. In front of this deviation prism an additional prism 5 is provided leaving a thin layer of air between it and the deviation prism. The purpose of this 70 additional prism consists in securing the entrance of the axial ray into the glass body at right angles to the entrance surface. The two reflecting surfaces of the deflection prism 4 are designated 6, 7, one part of the 75 surface 6 being as well the entrance surface for the light as a reflection surface against which the light is thrown after reflection from the further reflecting surface 7 and from which it is thereafter again reflected. The numeral 8 designates the objective for high magnification, said objective forming at the same time an element of the objective for low magnification, the two other elements of this objective for low 80 magnification being designated 9 and 10. The lenses 9 and 10 can be at will inserted into the path of the rays and brought out of the path of the rays, whereas the objective 8 is arranged in fixed position. 11 designates a collecting lens having its plain 85 backside lying in the first image plane of the instrument, such image plane being common to both objective systems. The image reversing system and ocular may have any 90 desired form. The ocular casing is indicated only in Fig. 4 of the drawing and designated with the numeral 12.

95 The actuation as well of the entrance reflector as of the lenses 9, 10 is effected by 100 two toothed racks 13, 14 which by coupling members 15, 16 are connected to racks 17, 18 provided at the lower end of the instrument. The racks 13, 14 are in mesh with

a pinion 19 on a shaft 20 which is provided at the end opposite the end carrying the pinion 19 with a crank 21 which by a link 22 is connected with the rotating entrance reflector 3 having its pivot at 23. 24 designates a toothed segment mounted on shaft 20 laterally of pinion 19, said segment adapted to come in mesh with a toothed rack 25 provided on the carrying member of the lens element 9. Formed in one piece with the toothed segment 24 is a circular segment 26 which is shown in Fig. 3 as resting in an arch-shaped cut 27 of the body of rack 25. The circular segment 26 locks the toothed rack 25 in position as long as it remains in the arc-shaped cut 27, but leaves it free for sliding movement on leaving said cut at which time the teeth of the segment 24 come into mesh with the teeth of the rack 25 so as to produce displacement of said rack. It appears from this that the entrance reflector 3 can be adjusted by actuation of the toothed racks 13, 14 without at the same time displacing the lens element 9 of the objective. The element 10 of the objective for low magnification is mounted in a rotatable body 28 having its pivot at 29, the rotatable carrier 28 of the lens element 10 is provided with an angular slot 30 forming a guide for a pin 31 fixed to rack 13. On raising and lowering of rack 13 a pin 31 moves in one branch of the angular slot 30, so that the rotatable body 28 with the lens 10 is not affected by such raising and lowering of rack 13, but is on the contrary locked in position. During the movement of pin 31 within slot 30 the circular segment 26 locks the rack member 25, so that the lens elements 10 and 9 are locked in position at the same time. On arriving of pin 31 at the edge 32 of the angular slot 30 the rotatable body 28 is rotated till the branch of the angular slot 30 which was in horizontal position is brought to vertical position. If now rack 13 is further raised, pin 31 is displaced within this part of the angular slot 30. During this period of movement the toothed sector 24 is in mesh with rack 25 and produces a displacement of the lens element 9. Such displacement continues till the circular segment 26 enters the arch-shaped cut 27 of rack member 25.

42 is an arc-shaped slot within the rotatable body 28 and 43 a fixed pin entering said slot 42, such pin limiting the rotative movement of the rotatable body 28. The actuation of racks 13, 14 and 17, 18 is effected by a handle 33 provided at the ocular end of the instrument, said handle being mounted on a rotatable shaft 34. Shaft 34 is provided with teeth 35 in mesh with a toothed wheel 36 adapted to actuate the racks 17, 18. Therefore, on rotating the handle 33 about shaft 34 an actuation of

racks 13, 14 takes place in such a manner that each time one rack is raised simultaneously with the lowering of the other rack.

The arrangement is conveniently made in this way, that the direction of the handle 33 coincides with the direction of vision of the instrument. The handle 33 is mounted on a core 37 in the form of a toothed rack 75 slidable in a socket 38.

Teeth 39 of core 37 are in mesh with teeth 40 on shaft 34. A displacement of the core 37 within the socket 38, therefore, produces a rotation of shaft 34 and consequently an operation of racks 17, 18, 13, 14. The dimensions of the several parts are so calculated that by moving the handle 33 with the core 37 within the socket 38 from one end position to the other, the lenses 9, 10 are transported from rest position to operative 80 position, so that such endwise movement of the handle effects a change in magnification, whereas the rotation of handle 33 with socket 38 controls the adjustment of the entrance reflector. 41 designates a locking 85 pin for the core 37 limiting a sliding movement in the two opposite directions.

The operation of the instrument as a whole is as follows:

Assuming observation is to be made with 95 low magnification, then the lens elements 9, 10 of the objective system are brought into the position appearing from the drawing. By rotating the handle 33 with the socket 38 about shaft 34 the instrument is adjusted 100 into the desired direction of vision. If now a change in magnification shall take place the handle 33 is moved in longitudinal direction, so that the core 37 is brought from one end position within socket 38 to the 105 other end position. During such movement the entrance reflector 3 makes a full up and down swinging and at the end of this movement is again in the same position as at the beginning. If the core 37 is returned to its 110 original position the magnification of the instrument is again changed and all parts of the instrument are returned to their original position.

Instead of effecting the adjusting movements by moving the handle 33 in longitudinal direction and by rotation of same about shaft 34, the longitudinal movement could be substituted by a rotation of the handle about the axis of core 37. 115

The arrangement of the fixed objective 8 behind the deviation prism 4 is of special advantage in so far that it allows to position the first image plane, which is common to both objective systems, at considerable 125 distance from the light entrance end of the instrument. This is important for securing a comparatively small diameter for the light entrance end of the instrument till a considerable distance from plate 2, 130

owing to the fact that the bulk of the rays broadens itself laterally behind the image plane 11, so that it becomes necessary to broaden also the instrument tube behind

5. the image plane 11.

What we claim is:

1. In a periscope particularly for submarines, a light entrance reflector rotatable about an axis transversely to the main tube 10 of the instrument and a prism firmly mounted within the casing of the instrument inserted in the path of the rays coming from the entrance reflector said last named prism adapted to deflect the rays impinging thereon by two successive reflections into the direction of the main tube of the instrument.
2. In a periscope particularly for submarines, a light entrance reflector rotatable about an axis transversely to the main tube 20 of the instrument, a prism device inserted in the path of the rays behind the entrance reflector consisting of a main deviation prism provided with two reflecting surfaces, 25 one of them forming a light entrance surface of the prism and an additional prism in front of said entrance surface of the main prism so shaped and positioned that its entrance surface is at right angles to the axial ray of the instrument.
3. A periscope particularly for submarines comprising a tube shaped casing containing the optical elements of the instrument, said casing closed at the light entrance end by a plane transparent plate inclined to the axis of said tube, an objective firmly mounted within said instrument tube and a prism device positioned between said inclined transparent plate and said 35 fixedly mounted objective, said prism device comprising a light entrance reflector rotatable about an axis transversely to the axis of the instrument tube and so positioned that a section made through the instrument 40 at right angles to its axis containing the axis of the rotatable reflector crosses the axis of the instrument tube between said reflector axis and said inclined transparent plate.
4. In a periscope particularly for submarines, a light entrance reflector rotatable about an axis transversely to the main tube of the instrument, a deviation prism behind said rotatable entrance reflector adapted to 50 deflect the rays impinging thereon into the axial direction of the instrument tube, objective systems for different magnification, the objective device for the lower magnification comprising a negative element removably positioned between the rotatable entrance reflector and the deviation prism.
5. In a periscope particularly for submarines, a light entrance reflector rotatable about an axis transversely to the main tube 60 of the instrument, a deviation prism behind

said rotatable entrance reflector adapted to deflect the rays impinging thereon into the axial direction of the instrument tube, objective systems for different magnification, the objective device for the lower magnification comprising a negative element removably positioned between the rotatable entrance reflector and the deviation prism, the objective for the higher magnification firmly mounted behind the deviation prism. 70

6. In a periscope particularly for submarines, a light entrance reflector rotatable about an axis transversely to the main tube of the instrument, a deviation prism behind said rotatable entrance reflector, objective 80 systems for different magnification, and a guide-way between the rotatable entrance reflector and the deviation prism, the objective device for the lower magnification comprising a negative element slidably arranged on said guide-way and adapted to be at will inserted into the path of the rays and removed therefrom.

7. In a periscope particularly for submarines, a light entrance reflector rotatable about an axis transversely to the main tube 90 of the instrument, a deviation prism behind said rotatable entrance reflector and an actuating device for said entrance reflector comprising at least one toothed rack, a crank shaft, a pinion thereon meshing with said toothed rack and a link connecting said crank shaft with said entrance reflector.

8. In a periscope particularly for submarines, a light entrance reflector rotatable about an axis transversely to the main tube of the instrument, a deviation prism behind said rotatable entrance reflector, objective 100 systems for different magnification and comprising elements adapted to be inserted into the path of the rays and to be removed therefrom and an actuating device for said entrance reflector and movable object glass elements, said actuating device comprising 105 at least one toothed rack in operative connection as well with the entrance reflector as with the movable lens elements, the connection with the movable lens elements being of such kind that a reversal of the lens 110 positions is only effected on a full working stroke of the rack.

9. In a periscope particularly for submarines, a light entrance reflector rotatable about an axis transversely to the main tube of the instrument, a deviation prism behind said rotatable entrance reflector, objective systems for different magnification, the objective device for the lower magnification comprising a negative element, a guide-way 120 for same, said guide-way arranged between the rotatable entrance reflector and the deviation prism, a toothed rack slidable with the lens, an actuating device for said rotatable entrance reflector, a slidable nega- 125

tive lens comprising at least one toothed rack in operative connection with the rotatable entrance reflector, and a toothed segment adapted to mesh at predetermined positions with the rack connected to the slideable negative lens element.

10. In a periscope particularly for submarines, a light entrance reflector rotatable about an axis transversely to the main tube of the instrument, a deviation prism behind said rotatable entrance reflector, objective systems for different magnification, the objective device for the lower magnification comprising a negative element, a guide-way for same, said guide-way arranged between the rotatable entrance reflector and the deviation prism, a toothed rack slideable with the lens, an actuating device for said rotatable entrance reflector, a slideable negative lens comprising at least one toothed rack in operative connection with the rotatable entrance reflector, and a toothed segment adapted to mesh at predetermined positions with the rack connected to the slideable negative lens element, a locking device for the slideable negative lens being provided adapted to lock it at both its end positions, said locking device comprising an arcuate segment adapted to enter in arcuate cuts of the lens carrier.

11. In a periscope particularly for submarines, a light entrance reflector rotatable about an axis transversely to the main tube of the instrument, a deviation prism behind said rotatable entrance reflector, objective systems for different magnification, the objective devices comprising a slideable negative lens element, a fixed lens element and a rotatable lens element, a guide-way for the slideable lens element positioned between the rotatable entrance reflector and the deviation prism and a rotatable lens element, an actuating device for said rotatable entrance reflector and movable lens elements, comprising a toothed rack in operative con-

nnection with said rotatable entrance reflector and movable lens elements, the connection with the rotatable lens element being effected by a pin on the actuating rack working in an angular slot of the rotatable lens element and locking it in position while moving in each of the lateral branches of the angular slot but giving it a rotation of definite angular width on passing from one lateral branch of the slot to the other. 50

12. In a periscope particularly for submarines, a light entrance reflector rotatable about an axis transversely to the main tube of the instrument, a deviation prism behind said rotatable entrance reflector, objective systems for different magnification and comprising elements adapted to be inserted into the path of the rays and to be removed therefrom and an actuating device for said entrance reflector and movable object glass elements, said actuating device comprising a slideable toothed rack in permanent operative connection with the entrance reflector during its whole operative stroke and in operative connection with the movable lens elements only during the intermediate portion of its stroke, an operative handle for said actuating rack adapted to operate the rack by two different kinds of movement communicated to said handle, one 60 kind of movement being rotation about an axis transversely to the axis of the instrument tube, the transmission of the gear being so calculated that the position of the handle permanently indicates the actual direction of vision of the instrument. 70

In testimony whereof we have signed this specification in the presence of two subscribing witnesses.
